UNITED STATES PATENT OFFICE.

FRED DOOLITTLE, OF SAN BERNARDINO, CALIFORNIA.

ADJUSTABLE BRUSH.

1,260,258.

Specification of Letters Patent. Patented Mar. 19, 1918.

Application filed May 11, 1917. Serial No. 167,908.

To all whom it may concern:

Be it known that I, FRED DOOLITTLE, a citizen of the United States, residing at San Bernardino, in the county of San Bernardino 5 and State of California, have invented new and useful Improvements in Adjustable Brushes, of which the following is a specification.

This invention is especially adaptable for 10 tooth brushes, and is herein shown embodied in such a structure.

The user of the common tooth brush finds it difficult to manipulate the brush to clean 15 the teeth in the approved up and down direction. This is because of the fixed relation of the handle and back, which makes it awkward to manipulate the brush in some portions of the mouth.

It is an object of this invention to provide 20 a brush having a back and handle relatively adjustable with respect to one another.

It is another object of this invention to provide a brush with a back which is detachable from the handle.

25 A still further object of this invention is to provide details of construction, whereby simplicity of structure and ease of operation of the brush are secured.

I accomplish these objects by means of the 30 embodiment of my invention illustrated in the accompanying drawing, in which:

Figure 1 is a plan view of a brush with the back and handle in one position.

Fig. 2 is a plan view of the brush with 35 the back and handle in another position.

Fig. 3 is a vertical section as seen on the line 3—3 of Fig. 1.

Fig. 4 is a side elevation of the handle and back detached.

40 The back 5 is of the usual form without the handle forming a part thereof, and embedded in the back are bristles 6. Upstanding from the back is a button 7; the button 7 is preferably of metal and molded or 45 pressed into the back.

A handle 8 is bifurcated at one end, as indicated by 9, so that the neck of the button may be received within the slot with the handle abutting the head of the button. Extending along the lower face of the handle 50 is a slot 10 which ends mid-way of the handle in an opening 11. It will be noted that the slot in the end of the handle is inclined, and disposed beneath this inclined portion 55 and extending along the slot 10 is a wedge

member 12. The end of the wedge member 12 is slotted so that it may embrace the neck of the button. The other end of the wedge member is bent upwardly and extends through the opening 11 forming a finger 60 piece 13.

Assuming the elements of the brush are in the position shown in Figs. 1 and 3; the wedge frictionally holds the brush back with respect to the handle. In order to 65 change the angular position of the handle, finger piece 13 is engaged by the thumb and the wedge member pushed forward into the position shown in Fig. 4. In this position the frictional pressure between the handle 70 and brush back is relieved, and the back may then be turned to a selected position. The wedge is then retracted by pulling upon finger piece 13 and frictionally holds the back and handle with respect to one an- 75 other.

If it is desired to detach the handle from the back, the wedge is pushed forward and the handle slipped from the neck of the button. The width of the slot in the end of 80 the wedge is such that the wedge may be slipped over the head of the button, and the handle removed. This permits cleaning of the brush, thereby making it sanitary, and also permits removal of the backs. A han- 85 dle may thus serve for a number of backs, the backs being replaced as they become worn.

What I claim is:

1. A brush, comprising in combination a 90 back having a button thereon, a handle pivotally mounted on said button, and a slidable wedge member interposed between the back and said handle, whereby the angular relation of said back and handle may be 95 adjusted.

2. A brush, comprising in combination, a back having a button thereon, a handle provided with a slot in which the neck of said button is disposed, and a slidable wedge dis- 100 posed between said back and said handle, whereby the angular relation of the back and handle may be adjusted.

3. A brush, comprising in combination, a back having a button thereon, a handle piv- 105 otally secured to said button, a wedge mem- ber having a slotted end embracing the neck of said button and disposed between the handle and back, said wedge member ex- tending along said handle and being pro- 110

vided with a finger piece for adjusting the same.

4. A brush, comprising the combination of a back, having a button thereon, a handle 5 provided with a slot at one end in which said button is disposed, a wedge having a slotted end embracing the neck of said button, said wedge extending along said han-

dle and being provided with a finger piece, whereby the handle may be detached from 10 the back and the angular relation of the back and handle adjusted.

In witness that I claim the foregoing I have hereunto subscribed my name this 25th day of April, 1917.

FRED DOOLITTLE.
